UNITED STATES PATENT OFFICE.

ISAAC A SHEPPARD, OF PHILADELPHIA, PENNSYLVANIA.

DESIGN FOR STOVE-DOORS.

Specification forming part of Design No. 7,803, dated October 13, 1874; application filed September 23, 1874.
[Term of Patent 14 years.]

To all whom it may concern:

Be it known that I, ISAAC A. SHEPPARD, of Philadelphia, Pennsylvania, have produced or invented a Design for a Stove-Door, of which the following is a specification:

My design for a stove-door is clearly illustrated by the accompanying drawing, the main feature of the design being the central medallion A, surrounded by the oval ornament B, which consists of the bead f, having a series of spear-like points, b.

The chief characteristics of the medallion A are the central star-like figure a, within the oval beaded band d, from the sides and ends of which project the foliated ornaments e. The door has at its edge the usual plain bead.

I claim—

1. The design for a stove-door, having a central medallion, A, consisting of a central star-like figure, a, oval beaded band d, and radiating foliated ornaments e, as illustrated and described.

2. The design for a door, in which the medallion A is surrounded by an oval ornament, B, consisting of the bead f and spear-like radiating points b, substantially as shown and described.

In testimony whereof I have signed my name to this specification in the presence of two subscribing witnesses.

ISAAC A. SHEPPARD.
